UNITED STATES PATENT OFFICE

FRANK R. BECKERT, OF SCHENECTADY, NEW YORK, ASSIGNOR TO GENERAL ELECTRIC COMPANY, A CORPORATION OF NEW YORK

ELECTRIC DISCHARGE DEVICE

Application filed December 27, 1928. Serial No. 328,739.

My invention relates to electric discharge devices such as mercury arc rectifiers for example, and has for its principal object the provision of an improved resilient and conductive lead-in conductor for such devices.

In mercury arc rectifiers, it is sometimes desirable to use grid or control electrodes for controlling the current flow from each anode and for protecting the anodes from arc-back 10 during the negative half cycle of the potential applied to the rectifier. The control electrodes are of various forms but must be insulated in each instance from the conductive walls of the rectifier, and must be mounted 15 near the end of the anodes. The anodes are mounted within sleeves to protect them from mercury particles emitted from the cathode, and the control electrodes are therefore, also mounted within the sleeves. Because of this 20 mounting the electrodes are inaccessible and it is difficult to attach to them a lead-in conductor which must necessarily be attached after the electrode is mounted within the anode sleeve. The lead-in conductor projects 25 through and is insulatingly sealed to the wall of the rectifier by means of a vitreous material such as glass.

It has been customary to thread the lead-in conductor into a tapped hole in the wall of 30 the electrode. This method has the disadvantage that it is difficult to thread the conductor into this hole and due to the unequal expansion of the walls of the rectifier and the lead-in conductor, the conductor seals were 35 quite often broken.

In accordance with my invention these difficulties are overcome by providing a resilient and conductive member supported by the grid or control electrode and arranged to engage 40 the lead-in conductor.

My invention will be better understood from the following description when considered in connection with the accompanying drawing and its scope will be pointed out 45 in the appended claims.

Referring to the drawing, Fig. 1 illustrates a section of a mercury arc rectifier illustrating one of the anodes, control electrodes and the lead-in conductor attached to the latter 50 in accordance with my invention. Figs. 2 and

3 illustrate details of the lead-in conductor and its connection to the electrodes and Fig. 4 illustrates a modification of my invention.

Fig. 1 illustrates a section of a rectifier casting 10, a sleeve 11 attached thereto and forming a recess for the anode 12. A sleeve 13 projecting into the tank 10 is mounted at the lower end of sleeve 11 and supports a funnel shaped baffle or nozzle 14 which directs the rectifying arc toward the tip of the anode 12. A control electrode 15 comprising a metallic sleeve 16 having a wire screen 17 across its end is supported by an insulator 18 within the sleeve 11 directly below the anode 12.

A lead-in conductor 19 surrounded by an insulating sleeve 20 projects through a metallic sleeve 21 attached to and projecting through the wall of cylinder 11 and a casing 22. The casing 22 surrounds tank 10 and forms a water jacket about the tank through which cooling water is circulated during the operation of the rectifier.

The lead-in conductor 19 terminates in a member 23 which is sealed by means of a glass seal 24 to a member 25. The member 25 is in turn attached to the sleeve 21 by means of a member 26. The aluminum wire gasket 27 provides a vacuum tight joint between these two members.

It is evident that the electrode 15 is quite inaccessible and that it is difficult to obtain a good conductive connection between it and the lead-in conductor. I have therefore in accordance with my invention provided a cup shaped member 28 which is attached to the electrode 15 and supports a coil spring 29. The spring 29 is a helical coil of sufficient length and diameter so that when it is coiled within the cup 28 the circle formed by the inner extremities of its turns is slightly smaller than the diameter of the lead-in conductor 19. The member 28 is welded or otherwise attached to the control electrode 15 and its walls are turned in after spring 29 is placed therein so that the latter is held in place within the cup.

When assembling the rectifier the electrode 15 is placed so that member 28 will line up with sleeve 21 with only a fair degree of ac-

curacy. The lead 19 is then simply inserted into the sleeve 21 and pushed down until its lower end is gripped by the resilient turns of the spring 29. The resiliency of the spring and the diameter of the turns thereof provide the means to offset any misalignment of the sleeve 21 and member 29. A resilient conductive connection is thereby formed which permits relative movement between the conductor and the electrode and may be easily made.

In occasional instances I have found it necessary to assemble the lead to the control electrode before it is mounted in the anode sleeve, or within the rectifier tank, and to complete the seal after it has been so mounted. For such instances I have modified my invention as illustrated in Fig. 4. The resilient connection in this construction is made between the terminal member 30 and the lead 31. Lead 31 is a straight conductor threaded into the electrode sleeve 16 and extending back into the member 30. Member 30 corresponds to a combination of the members 23 and 28 of Fig. 1 and the spring 29 is held therein as in part 28. The conductor 31 is made long enough so that it extends past the spring 29 and may freely expand or contract without interfering with its contact between the spring and itself and without injury to the glass seal 24.

What I claim as new and desire to secure by Letters Patent of the United States, is:

1. An electric discharge device provided with an electrode mounted within an evacuated vessel, a sleeve connected to a wall of said vessel and projecting outwardly thereof, a terminal supported by and insulated from said sleeve, a connection including a rigid member and a helical spring interposed between said electrode and said terminal, said sleeve enclosing a portion of said rigid member, and a cup-shaped member mounted upon said electrode for supporting said spring.

2. An electric discharge device provided with an electrode mounted within an evacuated vessel, a terminal insulated from said vessel, a connection including a resilient member and a rigid member adapted slidably to engage said resilient member, said connection being interposed between said electrode and said terminal, means to mount said resilient member upon said electrode, and means including a sleeve connected to said vessel and enclosing a portion of said rigid member to guide said rigid member into engagement with said resilient member.

3. An electric discharge device provided with an electrode mounted within an evacuated vessel, a terminal insulated from said vessel, a connection including a helical spring and a rigid member adapted slidably to engage said helical spring, said connection being interposed between said electrode and said terminal, means to mount said helical

spring closely adjacent said electrode and in electrical connection therewith, and means including a tubular member connected to said vessel and enclosing a portion of said rigid member to guide said rigid member into engagement with said spring.

In witness whereof, I have hereunto set my hand this 26th day of December, 1928.

FRANK R. BECKERT.
